UNITED STATES PATENT OFFICE.

AMOS N. HOAGLAND, OF OXFORD, NEW JERSEY.

SPARK-PLUG.

1,154,117.

Specification of Letters Patent. Patented Sept. 21, 1915.

Application filed August 2, 1911. Serial No. 641,905.

To all whom it may concern:

Be it known that I, AMOS N. HOAGLAND, a citizen of the United States, and a resident of Oxford, county of Warren, and State of New Jersey, have invented a certain new and useful Improvement in Spark-Plugs, of which the following is a specification.

My invention relates to spark plugs which are adapted for the ignition of explosive charges in hydro-carbon engines.

Among the objects of my invention are the provision of a spark plug with multiple sparking points; the provision of a spark plug in which the point or points are readily movable and removable and replaceable, the provision of a spark plug which is not readily fouled and in which the insulation and inner conductor is protected from fouling by the means carrying the sparking points, and the provision of a spark plug in which the distance between the points is adjustable to control the length of the spark gap by positive adjusting means without the necessity of resorting to bending of parts or deformation of any character.

Other objects of my invention will appear in the course of the following specification and claims.

With these and related objects in view, my invention consists in the parts, improvements and combinations hereinafter set forth and claimed.

While I have illustrated and shall describe the preferred embodiment of my invention, it will, of course, be understood that my invention is not limited to the specific form illustrated and described, but is as broad as my claim.

In the accompanying drawings in which the same numerals of reference are uniformly used to designate the same parts throughout, Figure 1 is a vertical, central, cross-sectional view of a spark plug embodying the preferred form of my invention, and Fig. 2 is a similar fragmentary view of a modification.

Reference numeral 1 designates the outer shell of the spark plug. This shell may be of any known form. In the illustration I have shown it as having a threaded portion 2 adapted to be screwed into a threaded opening in the engine cylinder, and a squared or hexagonal portion 3 to which a wrench or other tool can be applied. In the form shown a shoulder 4 is formed between the screw-threaded and the squared or hex-

agonal portion, but as already stated, this shell may be of any preferred and usual form, according to the form and construction of the cylinder in which it is to be used. 60

Reference numeral 5 designates the insulating means which is preferably of porcelain, but, of course, any equivalent insulator may be substituted for the porcelain. The insulator 5 is provided with an enlarged portion 6 between its ends, which is received fairly snugly within the opening 7 in the shell 1, and rests on the shoulder 8 in said shell. The insulator is held in place in the shell by means of the retaining nut 9 which is apertured at 10 to permit the passage of the insulator, and is provided with an exterior screw thread by means of which it is screwed within the interiorly threaded opening 7 of the shell 1. Suitable packing 11 is supplied at each end of the enlargement 6 of the insulator 5 in order to make the spark plug gas tight. The insulator 5 is provided with an axial perforation 12, which perforation is enlarged at its lower end to form the recess 13. Through this longitudinal perforation in the insulator is passed the stem 14 of conducting material. Near its lower end, this stem, which is preferably threaded substantially throughout its length, is enlarged at 15 to an extent nearly but not quite sufficient to close the end of the recess 13, thus making a substantially dead air space within the interior of the recess 13, retarding and preventing deposit of carbon therein, and greatly lessening the liability of the plug to become fouled and short circuited. The removable point carrying member 17 may be secured against the shoulder 16 provided at the lower end of enlargement 15. 70

This point-carrying member 17 is preferably provided with a central screw-threaded opening so that it may be screwed on the stem 14 to abut against the shoulder 16, and may be firmly secured in place by means of the lock nut 18. It is not essential, of course, that the point-carrying member 17 be threaded and screwed on the stem 14, it being only important that it is readily removable therefrom without disturbing the remaining elements of the spark plug. The member 17 has points 19 formed thereon, and the sparks are formed between one or more of these points and the neighboring end of the shell 1. The points may be integral with the member 17 as shown in Fig. 1, or may be formed of other material suit- 80

able for the purpose as shown at 19' in Fig. 2. A multiplicity of such points are provided, there being four such points in each of the forms illustrated. The member 17 is preferably conical in form and covers the greater portion of the end of the plug and serves to protect the interior of the plug both by covering the end of the plug and by deflection of the gases coming in contact with it.

Nut 20 is screw-threaded on the stem 14 above the shoulder 15, and is received within the recess 13 in the insulator 5, and abuts against the inner extremity thereof, thus providing means of adjustment of the stem 14 and the spark point-bearing member 17 which is attached thereto with reference to the shell 1 of the plug. A nut 21 is provided for securing the outer end of the stem 14 to the insulator 5, and an additional nut 22 is provided for the purpose of making the requisite electrical connection.

If it is desired to adjust the plug so as to increase or decrease the length of the spark gap, this result may be secured by loosening nuts 22 and 21 and rotating the threaded stem 14 with respect to the nut 20 in which manner the points 19 may be made to approach or recede from the end of the shell 1. When it is desired to replace the spark points the nut 18 and spark point carrying member 17 (if the latter is screw-threaded on the stem) are unscrewed from

the stem 14 and the point-bearing member can then be replaced as readily and as often as desired, and without any interference with or disturbance of the remaining elements of the plug.

The entire spark plug when made as above described, is extremely simple and can be very cheaply constructed and readily maintained in an effective condition.

Having now described my invention, I claim:—

In a spark plug, an outer shell of conducting material, and having a central longitudinal aperture, an insulator within the aperture in the said shell, said insulator being provided with a longitudinal aperture enlarged at its inner end, a stem passing through the aperture in said insulator, and a nut on the said stem fitting within the enlargement of said aperture, said stem being enlarged beyond the said nut to substantially close the aperture in the insulator, a shoulder on said stem, and a point bearing member carrying a plurality of spark points removably secured to said stem and abutting against said shoulder, substantially as set forth.

This specification signed and witnessed this 31st day of July, 1911.

AMOS N. HOAGLAND.
